UNITED STATES PATENT OFFICE.

JOACHIM MAIDHOE, OF NEW YORK, N. Y.

DESIGN FOR DRESS-TRIMMING.

SPECIFICATION forming part of Design No. 18,957, dated March 12, 1889.

Application filed February 13, 1889. Serial No. 299,741. Term of patent 3½ years.

To all whom it may concern:

Be it known that I, JOACHIM MAIDHOE, residing and doing business in the city of New York, in the county and State of New York, 5 have invented and produced a new and original Design for Dress-Trimmings, of which the following is a specification, reference being had to the accompanying drawing, forming a part thereof.

- 10 The figure of the drawing illustrates my design for dress-trimmings applied to a dress. The body section of the design consists of a cylindrical collar figure, A, upon which figure cord-like lines are produced, so as to present a surface appearance of being interwoven, and at the center of the collar figure a rosette-like figure, B, is arranged. An essentially-triangular figure, D, is pendent from the collar figure, and from the said triangular figure, 15 which is similar in facial appearance to the collar figure above mentioned, conical figures D' are pendent, and likewise a series of figures, E, which latter figures consist of a series of vertically-drawn curved lines, in imitation 20 of a twisted cord, and grouped horizontal lines

representing cylindrical essentially-tapering figures. The entire figures E have the appearance of being drooped downward and festooned upward at the bottom, at which point they appear to all terminate in a rosette 30 figure, F.

The girdle-section of the design consists of a rosette-like figure, G, pendent, rosette-like figures G', likewise pendent, rectangular figures H, the surface of which figures is 35 covered with cord-like lines having the appearance of being interwoven. At the bottom of the rectangular figures a spherical figure, H', is arranged. Below the spherical figure a bell-like figure, H², appears, and a 40 group of tassel-like figures, H³, are pendent from the bell figure.

I claim—

A design for dress-trimmings, substantially as herein shown and described.

JOACHIM MAIDHOE.
